V. D. CARROLL

REGULATOR

Filed Dec. 9, 1922

Frumentor:
Vincent D. Carroll
Jonee Bain Hunkle Attest

UNITED STATES PATENT OFFICE.

VINCENT D. CARROLL, OF CHICAGO, ILLINOIS.

REGULATOR.

Application filed December 9, 1922. Serial No. 605,956.

To all whom it may concern:

Be it known that I, VINCENT D. CARROLL, a citizen of the United States, residing at Chicago, in the county of Cook and State of Illinois, have invented certain new and useful Improvements in Regulators, of which the following is a specification.

This invention relates to regulators, and has especial reference to fuel-gas regulators.

One of the objects of the invention is to provide an improved regulator for controlling a fluid-fuel to maintain a substantially constant pressure in a container to which heat, produced by combustion of the fluid-fuel, is applied.

A special object is to provide a reliable, accurate, compact and inexpensive regulator to control the heat applied to coffee urns, such as used in restaurants, hotels and the like.

Another object is to provide a device to regulate fluid-fuel and safe-guarding means to prevent liquid, steam and condensed steam from reaching the fluid-fuel conduits or containing chambers.

Another object is the provision of a pressure safety valve and a vent and liquid discharge valve attached to the device to safe-guard the container and the regulator.

Other objects and advantages will readily appear to persons skilled in the art from a consideration of the following description when taken in conjunction with the drawing forming a part hereof, wherein:

Fig. 1 is a side elevation of the device, showing parts in section.

Fig. 2 is an enlarged central section of Fig. 1 taken on line 2—2 of Fig. 3.

Fig. 3 is a section taken on line 3—3 of Fig. 2.

In all the views the same reference characters indicate corresponding parts.

The present invention is an improvement of the device disclosed in an earlier Patent No. 1,384,554 granted to me July 12, 1921.

In a manner generally similar to the device disclosed in the aforesaid patent, the present regulator provides a fluid controlled valve operable by variable pressure for regulating the supply of the heating medium to the burner of the container, the yielding means controlling the fluid-fuel being affected by pressure within the container in such manner that increase of pressure diminishes

the flow of fuel to the burner and decrease of pressure increases the volume of fuel sup-

ply, tending to maintain a constant pressure in the container. The structure of my present invention contains several advantageous refinements not present in my aforesaid patent.

The accompanying drawing, taken in conjunction with the following description, fully disclose the present invention of the device for controlling the fuel supply to a burner for heating the liquid contents of a container.

A structure embodying the invention provides the body or casing 5, having a central, vertical, elongated chamber 6 which is connected to a container, the contents of which is to be heated by a fluid fuel, by a pipe 7, the opening 8 for the pipe is shown in dotted lines merely to indicate its position in the opposite wall of the chamber 6.

Chambers 9 and 10 are separable by a float valve 11 operable by a float 12. Another chamber 13 is normally in communication with chamber 6 through openings 14 and 16 and valve port 15.

Chamber 9 is closed by a screw plug 17.

Chamber 18 is connected to chamber 13 by a U-shape pipe 19, which may be of aluminum, steel or like material, unaffected by mercury.

The fuel chamber 18 contains a float 20 having an upwardly extending stem 21, which carries a valve 22 and which closes the ports 23 when the float is sufficiently raised. The altitude of the valve 20 is determined by the pressure within the container with which the regulator is connected.

A fuel fluid or liquid source is connected to the device by an inlet pipe 24 and the burner by the outlet pipe 25.

The tube 19 is to be filled by mercury 26, or the like, and a portion of mercury is contained in chambers 13 and 18.

A plunger 27 having longitudinally extending grooves 28 is connected to a threaded stem 29 and is vertically movable to vary the head of the mercury in the chamber 18 as a means for adjusting the fuel valve 22. The stem 29 is threaded into the plug 30 so that the plunger may be held at any adjusted position.

A safety valve 31, to open automatically upon occasion of excessive pressure in chamber 6 consists of the fluted weight 32 held seated by the influence of gravity, is connected to chamber 6 by a pipe 33.

There is a central bore 34 thru valve 32

normally closed by valve 35 thru the influence of spring 36. A cap 37 is threaded to the casing 31 to retain the valves in place.

5 The valve 32 will open upon occasion of abnormal pressure in chamber 6 and valve 35 will open upon occasion of subnormal pressure due to condensation of vapor or steam in chamber 6.

10 A vent valve structure 38, such as used on radiators and the like in steam heating systems, is connected to chamber 6 in an opening indicated by dotted lines 39, but in this instance in the opposite side of the wall, 15 as shown in Fig. 1. This vent structure contains an expansible member 40, its upper end fixed to a vertically adjustable screw 41, its lower end forming a valve 42 to close the port 43 when steam or heated 20 vapor raises the temperature of the member 40.

In the operation of the device pressure from chamber 6 is communicated to chamber 13 thru the openings 14 and 16, this depresses 25 the mercury in chamber 13 and raises it in chamber 18, thus raising the float 20 and partially closing the ports 23 by the valve 22, thus restricting the flow of gas thru the pipe 25 to the burner (not shown). When 30 pressure in chamber 6, and the container to which it is connected, is decreased, the mercury in chamber 13 will rise and correspondingly fall in chamber 18, thus opening the fuel valve to a greater degree and supplying 35 more gas to the burner.

In the event that water or other liquid should find its way into chamber 6, it will flow into chamber 10, but before it can get into chamber 9 the float 12 will close the 40 valve ports 15 and shut off communication with chamber 13, hence water cannot be admitted into the chamber containing mercury.

To vary the pressure to be maintained in chamber 6 the plunger 27 may be raised or 45 lowered.

While I have herein shown and described a single embodiment of my invention it is manifest that changes may be made therein within the spirit and scope of the appended 50 claims.

For convenience of claim drafting I have called chamber 18 the first chamber; chamber 6 the second chamber and chamber 13 the third chamber.

55 Having described my invention, what I claim as new and desire to secure by Letters Patent, is:—

1. A fuel regulator, for maintaining substantially constant pressure in a container 60 to be heated by the fluid-fuel controlled

thereby, comprising a casing having three intercommunicating chambers, the first chamber having a float controlled valve to vary the flow of fuel therethrough and having a gas inlet and outlet pipe connected thereto; the second chamber for connection to a container to be heated by the fuel controlled by the aforesaid valve; the third chamber connected thru ports to the second chamber and connected to the first chamber by a conduit containing a mobile fluid and a float valve controlling the connection between the second and third chambers. 65

2. A fuel regulator, for maintaining substantially constant pressure in a container 70 to be heated by the fluid-fuel controlled thereby comprising a casing having communicating chambers, the first chamber having a float-controlled valve arranged to vary the flow of fuel and having an inlet and an outlet pipe connected thereto; the second chamber, for connection to a chamber to be heated by the controlled fuel; the third chamber connected thru ports to the second chamber; a float valve for controlling said 75 ports when the second chamber is partially filled with water, to close communication between the second and third chambers; a conduit between the first and third chamber; a mobile liquid in the conduit partially filling first and third chamber and a displacing plunger in the third chamber movable into said liquid to vary the head thereof in the first chamber. 80

3. A fuel regulator for maintaining substantially constant pressure in a container 85 to be heated by fuel controlled thereby comprising a casing having three parallel cylindrical chambers, the first and third chambers connected at their bottom ends by a conduit; a mobile liquid filling the conduit and partially filling the first and third chambers; a float in the first chamber; a valve operable thereby to control a fluid fuel; an intake and fuel outlet pipe connected to the first chamber; a second chamber for connection to said container and subject to the pressure therein, said second chamber connected to the third chamber thru a port normally open; a float valve operable by 90 water in the second chamber to close said port; a vent valve in the second chamber; a safety valve connected thereto and a plunger in the third chamber to control the quantity of said mobile fluid in the first chamber, thereby to vary the control of fluid fuel by 95 said fuel valve. 105

In testimony whereof I hereunto subscribed my name.

VINCENT D. CARROLL.
